UNITED STATES PATENT OFFICE.

LOUIS BORGENICHT, OF NEW YORK, N. Y.

CHILD'S DRESS.

1,283,643.

Specification of Letters Patent.

Patented Nov. 5, 1918.

Application filed October 26, 1916. Serial No. 127,747.

To all whom it may concern:

Be it known that I, LOUIS BORGENICHT, of the city, county, and State of New York, have invented certain new and useful Im-
5 provements in Children's Dresses, of which the following is a specification.

My invention relates in general to a child's dress and particularly relates to a two-piece dress, each piece of which is a
10 complete article of commerce in itself.

The primary object of the invention is to provide a simple form of child's dress of the class described which can be readily arranged to give either one of two effects
15 simply by varying the manner in which the two pieces are assembled.

I attain this object broadly by providing a particular form of blouse with buttons both inside and out at the waist portion
20 and position a skirt as described either over or under the lower portion of the blouse and fasten the same to the proper line of buttons.

Various other objects and advantages of
25 the invention will be in part obvious from an inspection of the accompanying drawings and in part will be more fully set forth in the following particular description of one form of garment embodying my invention, and the invention also consists in certain new and novel features of construction and combination of parts hereinafter set forth and claimed.

Referring to the accompanying drawings:—

Figure 1 is a front elevation of a two-part dress constituting a preferred embodiment of my invention, with the parts assembled to form a simple blouse and skirt effect and with parts broken away to show the interior buttons;

Fig. 2 is the same dress assembled to form a Russian blouse effect.

In the drawings there is shown an upper
45 body garment 3 hereinafter identified as a blouse having a belt portion 4 and a short skirt portion 5 extending below the belt portion. The blouse is fastened down the front by means of fastening devices such as the
50 buttons and button hole connection 6 and in other respects resembles the conventional form of such articles of apparel now in general use. The following in appearance of the conventional form of one known type is
55 carried out by providing a deep belt 7 at the belt portion which belt is fastened to the

garment and laps across the front opening. The blouse also includes conventional forms of vertically extending plaits 8 which pass across the belt portion at front and back and extend to the shoulders of the garment.

The blouse differs from the known forms of such articles, however, in that the belt portion is provided with two lines of buttons. One line of buttons is fastened to the blouse exteriorly of the same with certain of the buttons 9 fastened to the plaits and others 10 fastened to the belt between adjacent plaits.

The other line of buttons 11 is fastened to the inside of the blouse preferably with the threads fastening the button on one side passing through the belt and plain blouse or through the belt and plaited portion of the blouse to similarly fasten the corresponding button on the opposite side. This particular locating of the buttons reinforces the material of the blouse for strains on the buttons are transferred partly at least to the belt and partly to the plaits. As these plaits extend to the shoulder of the wearer the strains are distributed along double thicknesses of material and tendency toward distortion of the garment is minimized.

The lower part of the dress is formed of a separable skirt 12 having a relatively deep waist band 13. This band is provided with a plurality of vertically disposed button holes 14 arranged when in proper set position to engage the buttons of either the interior or exterior line.

When the separable skirt is fastened to the exterior buttons and covering up the skirt portion of the blouse a simple blouse and skirt effect is provided as shown in Fig. 1.

Should the separable skirt be fastened to the interior line of buttons with the blouse skirt partially over-draping the separable skirt, the Russian blouse effect shown in Fig. 2 is produced.

By means of an article of this character, four different garments are produced, the blouse and skirt may be used separately or either of the effects shown in Figs. 1 and 2 may be provided. The additional buttons in no way detract from the appearance of the dress and to all effects the conventional form of dress is preserved.

Further other effects may be produced, such for instance as providing a light blouse

and a heavy skirt. Due to the reinforcements provided by both the belt and shoulder plaits the weight of the heavy skirt will have little if any effect on the blouse 5 for any pull will be taken up by the strong plaits.

Having thus described my invention, I claim:

- 10 1. A two-piece child's dress comprising a blouse provided with a belt portion and a short skirt portion extending below the belt portion, said belt portion provided with a line of buttons positioned exteriorly of the same and a line of buttons positioned on the 15 inside of the belted portion and a separable skirt provided with a waist band having button-holes for engaging the exteriorly positioned buttons with the skirt overlapping the skirt portion of the blouse to form a blouse and skirt effect or for engaging the 20 interior buttons with the skirt portion of the blouse overlapping the upper portion of the separable skirt to form a Russian blouse and skirt effect.
- 25 2. A two-piece child's dress comprising a blouse provided with a belt portion and a short skirt portion extending below the belt portion, said belt portion provided with a line of buttons positioned exteriorly of the 30 same, a line of buttons positioned on the inside of the belted portion, a separable skirt provided with a waist band having button-holes for engaging the exteriorly positioned buttons with the skirt overlapping the skirt 35 effect or for engaging the interior buttons

with the skirt portion of the blouse overlapping the upper portion of the separable skirt to form a Russian blouse and skirt effect and a belt for reinforcing the belt portion of the blouse at the lines of buttons.

3. A two-piece child's dress, comprising a blouse provided with a belt portion and a short skirt portion extending below the belt portion, said belt portion provided with a line of buttons positioned exteriorly of the same, a line of buttons positioned on the inside of the belted portion, a separable skirt provided with a waist band having button-holes for engaging the exteriorly positioned buttons with the skirt overlapping the skirt portion of the blouse to form a blouse and skirt effect or for engaging the interior buttons with the skirt portion of the blouse overlapping the upper portion of the separable skirt to form a Russian blouse and skirt effect, said blouse including a plurality of plaits extending across the belt portion to the shoulder portion of the blouse with certain of said buttons fastened to the plaits, said plaits designed to transmit strains on said certain buttons to the shoulder portion of the blouse.

Signed at New York city in the county of New York and State of New York this 23rd day of October, A. D. 1916.

LOUIS BORGENICHT.
